(57) **CLAIM**

The ornamental design for a bipod adapter, as shown and described.

DESCRIPTION

FIG. 1 is an isometric view of a bipod adapter showing our new design;

FIG. 2 is another isometric view of the bipod adapter shown in FIG. 1;

FIG. 3 is a front elevational view of the bipod adapter shown in FIG. 1;

FIG. 4 is a right side elevational view of the bipod adapter shown in FIG. 1;

FIG. 5 is a rear elevational view of the bipod adapter shown in FIG. 1;

FIG. 6 is a left side elevational view of the bipod adapter shown in FIG. 1;

FIG. 7 is a top plan view of the bipod adapter shown in FIG. 1; and,

FIG. 8 is a bottom plan view of the bipod adapter shown in FIG. 1.

The broken lines shown in the Figures are included for the purpose of illustrating portions of the bipod adapter that form no part of the claimed design.

1 Claim, 4 Drawing Sheets
